Primary Examiner — Jennifer L Rempfer*Assistant Examiner* — Aaron C Fowler(74) *Attorney, Agent, or Firm* — Curtis L. Harrington; Harrington & Harrington(57) **CLAIM**

The ornamental design for a vehicle flag mount, as shown and described.

DESCRIPTION

FIG. 1 is a left upper perspective view of a vehicle flag mount showing my new design;

FIG. 2 is a left side elevational view thereof, the right side being a mirror image;

FIG. 3 is a front elevational view thereof;

FIG. 4 is a rear elevational view thereof;

FIG. 5 top plan view thereof; and,

FIG. 6 is a bottom plan view thereof.

The dash-dot even broken lines illustrate and surround portions of the vehicle flag mount that form no part of the claimed design.

1 Claim, 2 Drawing Sheets
